UNITED STATES PATENT OFFICE

GEORGE AMBUEHL, OF EVANSTON, ILLINOIS

MOLD FORMING APPARATUS

Application filed April 2, 1932. Serial No. 602,733.

My present invention relates to the provision of mold forming apparatus, or apparatus for facilitating the investment of patterns or models for the purpose of providing a mold in which objects of the configuration of the patterns or models may be cast.

As will hereafter be seen, the facilities which I provide are peculiarly suitable for making molds for casting objects of small 10 dimensions, such as crowns and inlays for teeth.

The present method, so far as I am aware, for making molds for casting crowns and inlays consists in placing the pattern or model 15 formed of wax or some other fusible or combustible material, upon a post or sprue, which sprue is supported in a chamber, and the investing material, consisting of plaster of Paris or some like material mixed with sufficient water so as to readily flow, is poured 20 into the chamber and the plaster of Paris settles or gravitates about the form or pattern and solidifies. After the solidification of the investment material and the sufficient drying 25 thereof the post or sprue is withdrawn and the mold heated so as to drive off the fusible or combustible material of which the model or pattern is made through the channel left by the withdrawal of the post or sprue.

The above described process of investing 30 the model and forming a mold requires care and experience in order to secure satisfactory results as more or less air remains associated with the particles of the investment material which sometimes accumulates to form voids 35 in the mold and always operates to reduce the density of the mold even where appreciable size voids are not produced. Also the mixture of the investing material with the water is not always homogeneous, and over-wet portions 40 of the mold, when it is dried, also produce cavities or voids in the completed molds.

As will hereafter be seen my apparatus secures molds of greater and more uniform density and operates to extract a considerable 45 quantity of the water which would otherwise require to be dried out, thereby considerably shortening the time necessary in the forming of the molds.

I had as my objects the provision of the 50 facilities for conveniently and quickly in-

vesting models and patterns in forming molds for casting and the production of such molds of greater and more uniform density.

I have attained the foregoing objects by means of the apparatus illustrated in the accompanying drawing, in which—

Fig. 1 is a vertical elevation, partially broken away, of a structure embodying my invention, and

Fig. 2 is a horizontal section on line 2—2 of Fig. 1.

Similar reference characters refer to similar parts throughout the respective views.

As will hereafter be seen, it has been my object to force the investment material intimately about the model or pattern by centrifugal action and for this purpose I provide an electric motor 5 mounted vertically upon a suitable base or standard 6. The motor

shaft 7 extends from the top of the motor 70 and upon the top of the motor shaft is mounted a nearly cylindrical casing 11, the upper end of which casing is open. The bottom 8 of the cylindrical casing is preferably quite thick and is provided centrally with 75 the recess or socket 9 for frictionally receiving and engaging the top of the motor shaft 7.

The vertical walls of the casing 11 slightly converge as they rise from the bottom of the casing, and adjacent the bottom of the 80 casing are provided through the vertical side walls opposite passageways 12. Upon the outside of the casing 11 so as to continue the passageways 12 are tubular embossments 13 having upon their ends enlargements or rims 85

14. Inside of the casing 11 the bottom walls thereof are curved spirally upwardly from lines extending opposite the leading edges of the passageways 12 to a line opposite the following edges of the opposite passageway so 90 that the vertical edges 15 of the upwardly curved portions align with and constitute elongations of the following side walls of the passageways 12 and constitute extensions and prolongations of the walls of the passage- 95 ways 12.

I have stated that the beginning of the spirals are at the leading edges of the passageways 12 and that the termination of the spirals or the vertical edges 15 are located at 100

the following edges of the passageways 12, and wish to be understood by this description as referring to the directions of rotation of the casing 11, as the vertical edges 15 extending upwardly from the bottom of the casing, when the casing is rotated, act as guides and baffles to direct the investing mixture through the passageways 12. Fitting over the rims 14 and embossments 13 are hollow caps 16, 10 the edges 17 whereof are thickened to fit behind the enlargements 14 and the closed ends of which caps are also preferably thickened in a slightly conical form, as at 18. The caps 16 are preferably made of a suitable 15 grade of flexible and elastic vulcanized rubber. The post or sprue 19 upon which the model or pattern 20 is mounted is thrust through the apex of the conically thickened portions 18 of the ends of the caps, and it 20 will now be seen that by providing such a conical thickening greater supporting power for the post or sprue 19 is secured and also a depression is formed in the mold about the channel provided by the withdrawal of the 25 post or sprue 19, which facilitates the introduction of the fused metal into the mold.

When the apparatus is assembled, as above described and illustrated, the current is supplied to the motor which rotates the casing 30 11. The investing material, mixed with water so as to run freely, is then poured into the casing 11 and in a few minutes the motor is turned off and it will be found that more than half the water used in making the investment mixture may be poured, free from 35 the investment material, from the casing and upon removing the molds from the rubber caps 16 they will be found to be appreciably more solid and compact than molds formed 40 in the ordinary way. By reason of the extraction of a considerable portion of the water, as above described, the final drying of the molds is much shortened.

It will also be found when a casting is 45 made that the investing material has been brought more uniformly and intimately adjacent the surfaces of the pattern or model, as most minute configurations upon the surfaces of the patterns or models are accurately 50 reproduced.

Having described my invention what I claim as new and desire to secure by Letters Patent is:

1. An apparatus for investing a pattern or 55 model comprising a casing disposed for rotation about its axis, means for rotating said casing, detachable chambers formed of flexible and elastic rubber communicating with the interior of said casing carried radially 60 by said casing, said detachable chambers affording means for supporting a pattern or model therein.

2. An apparatus for securing the investment of a pattern or model comprising a cas- 65 ing disposed for rotation about its axis,

means for rotating said casing, hollow embossments extending radially and horizontally from said casing, means within said casing for directing the centrifugal energy developed by its rotation through said embossments, hollow chambers formed of flexible and elastic rubber associated with said embossments and affording means for supporting a model or pattern within said chambers.
